REVOLVING SIGN

Filed May 1, 1925

Inventor
A. E. KLINE,

Say

Attorney

UNITED STATES PATENT OFFICE.

AMBROSE E. KLINE, OF BROOKVILLE, PENNSYLVANIA.

REVOLVING SIGN.

Application filed May 1, 1925. Serial No. 27,243.

This invention relates to an improved revolving sign utilized for advertising purposes.

The principal object is to so construct the head of the sign that it will be automatically rotated by the air currents striking it, whereby to obviate the necessity of employing mechanical, or electrical means for maintaining it in rotation to change the sign display as is ordinarily necessary.

Another feature of the invention is the means employed for supporting the revolving sign carrying head in an elevated position, the means being a standard upon which the head is mounted by thoroughly lubricated means for facilitating rotation and causing the head to be set into rotation even when a dull breeze is blowing.

A further feature is the means for centering and stabilizing the head upon the standard.

Other features of the invention will become apparent from the following description and drawing.

In the accompanying drawing forming a part of this application and in which like numerals are employed to designate like parts throughout the same:

Figure 1 is a perspective view of a revolving sign constructed in accordance with the present invention.

Figure 2 is a sectional and perspective view of the same with portions removed.

Figure 3 is a reduced horizontal section taken approximately through the center of the revolving head.

Referring to the drawing in detail, the reference character 1 designates a vertical standard. This is provided at its bottom with an appropriate base which is anchored in a concrete foundation, or embedded in the ground in an appropriate way to which it may hold it in an upright position. Observing Figure 2 it will be noticed that the standard is of hollow formation, and that a plug 3 is fitted into the open top thereof, this plug carrying a bearing block 4 which is fitted into a socket. It will be noticed that the bearing block is in turn provided with a socket, and this forms a seat for the reception of a journal 5 connected with the revolving sign carrying head. Under this arrangement the bearing block socket may be filled

with a lubricant, and inasmuch as the friction is reduced by the presence of a single journal pin, it is obvious that the head will rotate with ease.

The head comprises an open frame work structure embodying a plurality of individual frames 6 for reception of the different signs 7. The signs may be secured in the frame in any suitable manner. The type of head shown is of hexagonal cross section, but the cross sectional shape may be varied to accommodate varying conditions. The top and bottom arms 8 and 9 which the frame work includes, are disposed in the radial relation shown. The aforesaid journal pin 5 is so constructed that it serves to connect the inner ends of the top arms 8 together. It will also be noticed as indicated in dotted lines that a disc 10 and appropriate ornament 11 is associated with the journal forming pin. The pin is thus permitted to connect the arms together, to serve as a journal for the revolving head, as a means for holding the disc 10 in place and also supporting an ornamental element 11. The plate 10 serves as a shield to prevent accumulation of water in the oil receiving socket in the bearing.

A stop collar 12 is fixedly connected to the standard as indicated more plainly in Figure 2, and this collar carries a depending annular flange 13 within which an upstanding flange 14 on the connecting plate 15 is confined. The plate 15 serves to connect the inner ends of the lower arms together. Under this arrangement, the stability of the head is increased and the stop prevented from being lifted up and off of the standard.

An important distinction to be observed as shown plainly in Figure 3 is the specific construction of the sign frames 6. The vertical pieces of these frames as indicated at 16 are channel shaped in cross section, and are disposed at an angle with respect to the outer faces of the sign to form air collecting pockets. In this instance it will be noticed that the sign is connected on one vertical edge to an ineffective side of one channel shaped member 16, and at its opposite end terminates in spaced relation from the other channel shaped member. In this way an unobstructed air collecting pocket is provided, and the air currents are collected in

the pockets, and the entire head set into rotation without employing mechanical or electrical operating and driving means, such as is ordinarily necessary.

From the foregoing description it will be seen that I have evolved and produced a novel revolving sign, wherein the signs are changed from time to time to obtain a more effective advertising display. The entire head is substantially supported on the upper end of the standard by a single friction like journal, which as before stated embodies other additional functions to be noted. The head however is prevented from wobbling and moving upwardly by the coacting flanges and stop means at the bottom thereof. Thus while the device is susceptible to easy rotation from dull breezes, it is nevertheless very rigid, and not open to destruction from strong wind current. No doubt, persons skilled in the art to which the invention relates will be able to obtain a clear understanding of the invention and will appreciate the advantages and features which it embodies. Therefore a more lengthy description is thought unnecessary.

While the preferred embodiment of the invention has been shown and described, it is to be understood that changes coming within the field of invention claimed may be resorted to if desired.

Having thus described the invention, what

I claim as new and desire to secure by Letters Patent is:—

In a revolving sign of the class described, a standard having a bearing at its top, a sign carrying head surrounding the upper portion of the standard, said head being in the form of an open frame-work structure of general hexagonal form, said structure embodying individual rectangular sign frames and radiating top and bottom members, the vertical bars of said sign frames being of channel-shaped cross-section to form air collecting pockets, a centrally located journal forming pin carried by the inner end portions of said top members, said standard having a socket in which said pin is located, a shield associated with said top members and pin, and cooperating means between the lower radial members and the standards for increasing the rigidity of construction and preventing displacement of said pin from said socket, said means comprising a stop member on the standard adjacent the bottom of the head, a plate carried by said head, and cooperating annular flanges on said stop member and on said plate, said flanges being disposed in telescoping relation to prevent undue side swaying of said head when rotating.

In testimony whereof I affix my signature.

AMBROSE E. KLINE.
